LADY'S DRESS

Nathan Lehman, Brooklyn, N. Y., assignor to William Heller, Inc., New York, N. Y., a corporation of New York

Application June 14, 1947, Serial No. 754,620

1 Claim. (Cl. 2—74)

1

The present invention relates to ladies' dresses and is more particularly concerned with tubular fabrics of the type commonly sold in the piece-goods departments of retail stores to be fashioned by the unskilled purchaser into the finished dress.

It is among the objects of the invention to provide a tubular fabric of the above type which incorporates in its structure ornamental trimming for the bust portion and especially for the neckline thereof, which trimming contributes to the ease of fashioning the dress from the tube by the unskilled purchaser and contributes to the draping of the dress, even of a loose fitting dress and especially at the neckline of the wearer.

In the accompanying drawings in which is shown one of various possible embodiments of the several features of the invention,

Fig. 1 is a front view of one embodiment of the tubular fabric as sold at retail.

Fig. 2 is a plan view of the tube as it would appear if extended after being slit along the mid-line of the back.

Fig. 3 is a fragmentary perspective view with parts broken away of the dress prepared from the tubular fabric of Fig. 1.

Fig. 4 is a perspective view showing the general appearance of the dress in wear.

Fig. 5 is a sectional detail view on a larger scale taken on line 5—5 of Fig. 3.

Fig. 6 is a perspective view on a larger scale of one of the nailheads, and

Fig. 7 is a sectional view on a larger scale taken on line 7—7 of Fig. 3.

Referring now to the drawings, the tubular fabric 10 is preferably of knitwear such as jersey, of any color or pattern and of the type commonly knit on a circular loom. The tubular fabric is preferably sold in length suitable for a dress. It incorporates on its front near one end thereof a decorative pattern of metal attachments, preferably nailheads *h*. These may be chrome-plated to give a shiny appearance or may have a dull finish. In the particular embodiment shown, each nailhead comprises a cup-shaped member 11, each of which may if desired have a rosette-shaped embossed face and may be of diameter approximately three eighths inch or less or greater, as desired. Each nailhead has a plurality of tines 12 extending from the rim of the cup substantially at right angles to its face.

Preferably tines 12 flare out slightly from the rim of the cup, so that when inserted into the fabric of the front part of the tubular fabric they will gather up a small amount thereof and thus when the tines are then clenched over as at 12'

2

in Fig. 7, they will compress the fabric against the inner side of the cup at 13. The small excess of material thus drawn inward by the tines as they are clenched over will prevent tearing of the fabric due to excessive stretching. The nailheads *h* are held securely to the fabric by the combined action of the compression of the fabric against the sides of the cup by the tines and by the penetration of the ends of the reversely bent tines into the fabric as at 14. As the ends of the tines are bent into the cup, as shown in Fig. 7, there is no danger of injury from their points, either to the person or underclothes of the wearer.

While the nailheads may be arranged in any of 15 a multiplicity of possible patterns, the drawings illustratively show one such pattern defining an ornamental V-type neck, the lowermost nailhead *h*' being in the order of eight inches below the uppermost nailheads *h*2.

Desirably the back of the tube has marked thereon, as for instance by chalk line 15, an outline defining a selvage 16 at the interior of the neck line bordered by the nailheads *h*. Desirably further chalk lines 17 extend longitudinally at 20 equal distances from the symmetrically arranged nailhead pattern to define the lateral lines of cutting for the arm holes, desirably along the lateral folds in Fig. 1.

It will be seen that the purchaser of the tube 30 would simply cut with a pair of scissors along the course defined by the chalk lines 15, would hem in the selvage 16 thereby left and be guided in such operation by the inner border of the pattern of nailheads. The arm holes would be cut along lines 17 and hemmed as at 19. The shoulders would be stitched together, as shown at 18, laterally of the neck line, the upper edge of which would also be hemmed as at 19. Desirably also the lower end of the tube would be hemmed as 40 at 20.

One size of tubular fabric will fit girls and women of a wide range of sizes and shapes. Weighted as it is along its length by the distributed nailheads, the ornamental neck line will 45 fit the wearer neatly, without curling inward or drooping outward or otherwise detracting from the tailored appearance of the neck line and associated bust in wear, and this regardless of the size or shape of the wearer. The looseness of the tube below the bust is gathered at the waist line by any suitable removable belt 21, as suggested in Fig. 4, and the slimmer the wearer the greater the amount of gathering at the waist, again without detracting from the neat fit at the neck line. 50 Though the invention has its preferred utility

with an ornamental V-type neck, such as illustratively shown, it will be understood that it lends itself to a wide variety of designs or patterns of nailhead distribution, by which may be attained the ornamental and tailored appearance above set forth.

By the present invention a girl may, in a few minutes time, convert the tubular article of manufacture shown in Fig. 1 and sold at a relatively low price, into a dress the equivalent of which if purchased as such would cost several times the price of the tube.

As many changes could be made in the above construction and method and many apparently widely different embodiments of this invention could be made without departing from the scope of the claim, it is intended that all matter contained in the above description or shown in the accompanying drawings shall be interpreted as illustrative and not in a limiting sense.

Having thus described my invention what I claim as new and desire to secure by Letters Patent of the United States is:

As an article of manufacture, a seamless tube of knit fabric having affixed on one side and near one end thereof a pattern of cupped nailheads

with concave under-sides into each of which fabric of the tube is gathered, whereby the tube may be readily converted into a dress by stitching together that end thereof which is adjacent the nailheads to form shoulders with an intervening neck opening and by cutting sleeve holes in the sides, such otherwise loosely fitting dress being in wear readily gathered at the waist by means of a separate belt, the fabric between the consecutive nailheads being slightly stressed in wear by virtue of the gathering of fabric into the concavity of each nailhead, thereby in wear securely to retain the neckline against the body.

NATHAN LEHMAN.
